UNITED STATES PATENT OFFICE.

JAMES FERGUSON AND WILLIAM H. BENNETT, OF VANCOUVER, BRITISH COLUMBIA,
CANADA.

TELEPHONE-MOUTHPIECE DISINFECTANT.

1,390,896.

Specification of Letters Patent. Patented Sept. 13, 1921.

Application filed February 25, 1921. Serial No. 447,748.

To all whom it may concern:

Be it known that we, JAMES FERGUSON and WILLIAM H. BENNETT, citizens of the Dominion of Canada, residing at Vancouver, in the Province of British Columbia, Canada, have invented certain new and useful Improvements in Telephone-Mouthpiece Disinfectants, of which the following is a specification.

10 This invention relates to a means providing for effectively disinfecting the mouthpiece of a telephone, the same being simple in construction, easily applied and direct and lasting in its effect.

15 The invention is fully described in the following specification, reference being made to the drawings by which it is accompanied, in which:

Figure 1 is a perspective view and part 20 section of the essential part of the device.

Fig. 2, a similar view of the retaining ring by which the disinfecting device is held within the mouthpiece, and

Fig. 3 shows the application of the device 25 to the mouthpiece of a telephone, which is shown in section.

In these drawings 2 represents the mouthpiece of the telephone. Within this mouthpiece 2 is fitted a correspondingly shaped liner 3 of a suitable absorbent material, such 30 as gypsum.

This liner 3 is retained in position in the mouthpiece 2 by a ring 4, the outer edge of which fits over the outside edge of the 35 mouthpiece 2 and is flanged across the face of the mouthpiece and its liner.

From the edge of 4 portions 5 backwardly project which may be readily bent inward over the edge of the mouthpiece to hold the 40 ring thereagainst and retain the liner in the mouthpiece.

This absorbent liner 3 is impregnated with a suitable liquid disinfectant, such as creosol, that will destroy any disease germs 45 or bacteria that may affect a lodgment on the mouthpiece.

The liner 3 may be of any suitable material but is preferably molded of gypsum to which other ingredients are added to enable 50 it to set harder and be more durable in the

handling the bushings are liable to be subjected to. If the composition contains, say, ninety per cent. of gypsum the remaining ten per cent. may be composed of dextrin, alum, sulfate of zinc, borax, and glue, all of which 55 are intended to effect the hard setting of the gypsum and render it more durable.

Although we have described the composition of a suitable material to form an effective liner, we do not desire to be confined to 60 such composition, but claim a liner as described of any composition that will have the required absorbent properties to retain a sufficiency of the disinfectant and part with it slowly, and that will have sufficient 65 strength to enable a relatively thin lining to be used with a retaining means that will expose the entire inner surface of the liner.

If care is taken in the selection of the disinfectant, sufficient will be retained in the 70 liner to render it effective for from thirty to forty days, and as the liner 3 is enduring, its disinfecting properties can be replenished for a further period.

Not only does the device provide an 75 enduring and renewable means for disinfecting the mouthpiece, but its disinfecting properties do not depend on emanations alone as the entire mouthpiece is lined with a disinfecting surface.

Having now particularly described our invention, we hereby declare that what we claim as new and desire to be protected in by Letters Patent, is:

A disinfecting means for a telephone 85 mouthpiece, comprising the combination with it of a thin lining of plaster-like absorbent material conforming to the inner surface of the mouthpiece, which lining is impregnated with an enduring antiseptic, 90 and a ring adapted to fit the outer edge of the mouthpiece and flanged in the plane of its outer edge to engage and retain the lining, said ring having backwardly projecting portions adapted to be bent around the outer 95 edge and retain a hold of the mouthpiece.

In testimony whereof we affix our signatures.

JAMES FERGUSON.
WILLIAM H. BENNETT.
